NOODLE CUTTER

William N. Rettinger, Wisconsin Rapids, Wis.

Application March 27, 1936, Serial No. 71,240

1 Claim. (Cl. 107—21)

The present invention relates to new and useful improvements in noodle cutters and has for one of its important objects to provide, in a manner as hereinafter set forth, a device of this character embodying a novel construction and arrangement of adjustable gage through the medium of which the noodles may be sliced as desired.

Another very important object of the invention is to provide a noodle cutter of the aforementioned character which is compact and portable and which may be expeditiously secured in position for use on any suitable support, such as a table.

Other objects of the invention are to provide a noodle cutter of the character described which will be comparatively simple in construction, strong, durable, highly efficient and reliable in use, light in weight and which may be manufactured at low cost.

All of the foregoing and still further objects and advantages of the invention will become apparent from a study of the following specification, taken in connection with the accompanying drawings wherein like characters of reference 25 designate corresponding parts throughout the several views, and wherein:—

Figure 1 is a top plan view of a noodle cutter constructed in accordance with the present invention.

Figure 2 is a view in front elevation of the device.

Figure 3 is a detail view, showing the mounting of the adjustable gage, taken substantially on the line 3—3 of Figure 1.

Figure 4 is a detail view in section, taken substantially on the line 4—4 of Figure 2.

Figure 5 is a detail view in perspective of the adjustable gage.

Referring now to the drawings in detail, it will be seen that the embodiment of the invention which has been illustrated comprises a substantially arcuate frame 1 of any suitable metal. The frame 1 is fixed on a clamp 2 through the medium of which the device may be removably secured in position for use on a suitable support, such as a table. Fixed in the frame 1 and projecting horizontally therefrom is a feed trough 3 which may also be of any suitable metal.

Projecting from one end portion of the frame 1 is an integral ear 4. The reference numeral 5 designates a hand lever which is pivotally connected at one end, as at 6, to the ear 4 for swinging movement in a vertical plane adjacent the side of the frame 1 which is remote from the feed trough 3. At its free end portion the lever 5 terminates in a handle 7.

Rising from the other end of the frame 1 is an integral guide 8 for the lever 5. The reference numeral 9 designates bumpers at the ends of the

guide 8 for engagement by the lever 5. It will be observed that the guide 8 is arcuate to allow for the arc which the pivoted lever 5 describes in its movement. A grooved block 10 is fixed on the lever 5 and slidably engaged with the guide 8 for connecting said lever thereto. The reference numeral 11 designates a slicing knife or blade which is fixed on the lever 5 adjacent the frame 1.

Projecting outwardly from the lever 5 is a 10 socket 12 for adjustably receiving a shank 13. Mounted on the outer end of the shank 13 is an angular arm 14 which carries a gage 15. A set screw 16 is provided in the socket 12 for releasably securing the shank 13 in adjusted position. 15

It is thought that the operation of the device will be readily apparent from a consideration of the foregoing.

The gage 15 is adjusted to the desired position relative to the knife 11 and secured, as suggested 20 in Figure 3 of the drawings. The lever 5 is then elevated to substantially the position shown in Figure 2 of the drawings and the noodle is slid in the trough 3 beneath the knife 11 until arrested by the gage 15. The knife 11 is then swung 25 downwardly to sever the projecting portion of the noodle which may drop into a suitable receptacle provided for this purpose. Of course, the operation is then repeated. In Figure 1 of the drawings a noodle is shown in dotted lines and designated by the reference numeral 17. The bumpers 9 limit the movement of the lever 5 in opposite directions. When not in use the device may be expeditiously removed from the table or other support. The lever 5 may be tightened as desired 30 on its pivot 6 through the medium of nuts 18. A washer 19 is interposed between the lever 5 and the ear 4.

It is believed that the many advantages of a noodle cutter constructed in accordance with the 40 present invention will be readily understood, and although a preferred embodiment of the device is as illustrated and described, it is to be understood that changes in the details of construction and in the combination and arrangement of parts 45 may be resorted to which will fall within the scope of the invention as claimed.

What is claimed is:—

In a noodle cutter, a pivoted lever, a knife carried thereby, a gage plate including an angular 50 arm integral with the plate and offset therefrom and means for adjustably securing the plate to the lever in spaced parallelism with respect to the knife and comprising a socket projecting laterally from the lever and a shank projecting laterally 55 from the arm and slidably positioned in the socket.
